UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE-FRAME.

1,114,192.

Specification of Letters Patent. Patented Oct. 20, 1914.

Application filed April 21, 1914. Serial No. 833,441.

To all whom it may concern:

Be it known that I, WILLIAM M. SHEEHAN, a citizen of the United States, residing at the city of St. Louis, State of Missouri, have 5 invented a certain new and useful Improvement in Locomotive-Frames, of which the following is a full, clear, and exact description, such as will enable others skilled in the art to which it appertains to make and use 10 the same, reference being had to the accompanying drawings, forming part of this specification, in which—

Figure 1 is a plan view of a locomotive frame of my improved construction. Fig. 2 15 is a side elevational view of the frame. Fig. 3 is a cross sectional view taken approximately on the line 3—3 of Fig. 1. Fig. 4 is a cross sectional view taken approximately on the line 4—4 of Fig. 1. Fig. 5 is a cross sectional view taken approximately on the line 5—5 of Fig. 1. Fig. 6 is a sectional view 20 taken approximately on the line 6—6 of Fig. 1.

My invention relates generally to locomotive frames and more particularly to a one piece rear extension for the main frame of the locomotive.

Heretofore in the construction of locomotive frames and particularly the rear frame 30 or extension, it has generally been the practice to construct said rear frame or extension of separate castings or forgings, which after being properly assembled, are connected to the main frame by machine-fit bolts. Such 35 construction has many disadvantages for the reason that the strains and constant vibration developed when the frame is in service tends to loosen the joints between the assembled parts, thereby destroying the 40 stability of the frame and the alignment and position of the various bearings and brackets which receive certain devices particularly 45 associated with and carried by the rear frame or extension. Furthermore, by making the frame in several pieces, necessitates a considerable amount of machine work and other finishing; likewise the setting of a large number of rivets and bolts.

It is the principal object of my invention 50 to overcome the objectionable features just mentioned by casting the rear frame or extension in a single piece, and forming inte-

gral therewith the necessary brackets and bearings, thus producing a very strong, rigid and substantial structure which, in service, 55 effectually resists all strains to which it is ordinarily subjected, and which is not affected by the constant vibration developed in service.

With the above and other objects in view, 60 my invention consists in certain novel features of construction and arrangement of parts, hereinafter more fully described and claimed.

As shown in the accompanying drawings 65 my improved rear frame or extension includes a pair of parallel side members 10 which may be of any desired cross sectional shape, but for all practical purposes I prefer to make these side members in the form 70 of channels with inwardly presented flanges. The forward ends of the webs of these side members are provided with perforations 11 in order to receive bolts or like devices which serve as means for rigidly fixing the rear extension or frame to the side members A of 75 the main frame of the locomotive.

The forward ends of the side members 10 are united by transversely disposed integral webs or plates 12, and formed integral with 80 the inner edges of these plates is a transversely disposed wall or web 13, the lower edge of which is provided with a rearwardly projecting flange 14. This web or wall and its flange serve as a support and point of 85 connection for the front end of the locomotive fire box.

Formed integral with the lower portions of the members 10 immediately to the rear of the wall 13 are inwardly projecting horizontally disposed plates or brackets 15 which serve as supports for equalizer fulcrums.

Formed integral with the lower portions of the members 10 and to the rear of the equalizer fulcrums 15 are transversely disposed rails 16 which serve to reinforce and strengthen that portion of the frame or extension which is located immediately above the rear truck, and formed integral with the end portions of these rails and with the corresponding portions of the members 10 are plates 17 which serve as bearings and points of attachment for the pedestals B which receive the journal boxes of the rear truck.

Formed integral with the inner faces of the members 10 between the transverse rails 16 are pairs of vertically disposed ribs or flanges 18 which form guides or bearing ribs 5 for the springs C which are associated with the rear truck.

Formed integral with the members 10 to the rear of the rear one of the rails 16 are vertically disposed housings 19 through 10 which are formed openings 20, the same receiving and forming seats for the corresponding spring shackles D.

Formed integral with the members 10 to the rear of the housings 19 is a transversely 15 disposed vertical wall 21 provided on its lower edge with a forwardly projecting flange 22, said wall and flange serving as a support and point of attachment for the rear end of the locomotive fire box.

20 Formed integral with the rear ends of the members 10 and to the rear of the plate 21 is a structure which includes a horizontally disposed top plate 23, a bottom plate 24, an intermediate plate 25, a transversely disposed front end wall 26, and a pair of vertically disposed longitudinally extending walls 27 which are parallel with the members 10. Formed integral with the plates 24 and 25 are lugs 28, the same being provided with vertically aligned openings 29, which are adapted to receive the draw bar attaching pin.

The rear draw bar of the locomotive occupies the chamber 29 which is formed between the plates 24 and 25 and the longitudinally extending walls 27. The upper front face of the front wall 26 is notched or recessed as designated by 30 so as to form a support and seat for the cab bracket.

40 The top plate 23 serves as a base or bracket for the grate shaker cylinder. Formed integral with the forward ends of the members 10 are depending lugs or brackets 31 which are perforated transversely in order to serve as points of attachment for the clevises of the safety chains.

A rear extension for locomotive frames of my improved construction is very strong, can be readily produced inasmuch as it can 50 be easily cast in a single piece, and by forming integral with said frame a number of essential brackets, bearings and the like, much time, labor and consequent expense incident to the attaching of separate parts 55 can be saved. Furthermore, the elimination of joints in the frame does away with structural weaknesses which invariably develop when an assembled or fabricated structure is subjected to service strains and vibration.

60 A one piece casting can be produced in much less time and with less labor than a frame built up from a number of structural shapes and castings, which are united by bolts, rivets and the like, and it has been demonstrated 65 in practice that an extension frame cast in

one piece while of lighter weight has much greater strength and rigidity than a built up frame.

It will be readily understood that minor changes in the size, form and construction of the various parts of my improved extension frame can be made and substituted for those herein shown and described, without departing from the spirit of my invention, the scope of which is set forth in the appended claims.

I claim:

1. A rear frame for locomotives cast in a single piece and comprising a pair of side members, a series of transverse members, and there being a draw bar pocket formed in the rear end of said frame.

2. A rear frame for locomotives cast in a single piece and comprising side members, a series of transverse members, and equalizer fulcrums.

3. A rear frame for locomotives cast in a single piece and comprising side members, transverse members, and vertically disposed spring bearing ribs on the inner faces of 90 said side members.

4. A rear frame for locomotives cast in a single piece and comprising side members, a series of transverse members, and trailer truck spring guides.

5. A rear frame for locomotives cast in a single piece and comprising side members, a series of transverse members, and trailer truck spring shackles seats.

6. A rear frame for locomotives cast in a single piece and comprising side members, a series of transverse members, and safety chain clevis attaching brackets.

7. A rear frame for locomotives cast in a single piece and comprising a pair of side 105 members, and a series of transverse members, one of which serves as a bracket for the grate shaker cylinder.

8. A rear frame for locomotives cast in a single piece and comprising a pair of side members, and a series of transverse members, one of which serves as a support and point of attachment for the rear fire box connection.

9. A rear frame for locomotives cast in a single piece and comprising a pair of side members, and a series of transverse members, one of which serves as a support and point of attachment for the front fire box connection.

10. A rear frame for locomotives cast in a single piece and comprising a pair of side members, plates and webs uniting the forward ends of said side members, plates and webs uniting the rear ends of said members, and there being a draw bar pocket formed between the plates and webs at the rear ends of said members.

11. A rear frame for locomotives cast in a single piece and comprising side mem- 130

bers, end members, a pair of intermediate transverse members, and pedestal attaching plates integral with the end portions of said transverse members.

12. A rear frame for locomotives cast in a single piece and comprising a pair of side members, a series of transverse members, a pair of equalizer fulcrums, pedestal attaching plates, spring shackle seats, grate

shaker cylinder brackets, and safety chain 10 clevis brackets.

In testimony whereof I hereunto affix my signature in the presence of two witnesses, this 18th day of March, 1914.

WILLIAM M. SHEEHAN.
